Primary Examiner — Ryan Harvey(74) Attorney, Agent, or Firm — Falcon, Rappaport & Berkman LLP(57) CLAIM

The ornamental design for a dumbbell, as shown and described.

DESCRIPTION

FIG. 1 is a first perspective view of a dumbbell showing my new design;

FIG. 2 is a second perspective view thereof;

FIG. 3 is a front view thereof;

FIG. 4 is a rear view thereof;

FIG. 5 is a top plan view thereof;

FIG. 6 is a bottom plan view thereof; and,

FIG. 7 is a first end view thereof, the second end view being the same.

1 Claim, 3 Drawing Sheets(56)
